SNAP ACTION SADIRON LIFT

George Browning, Wilmette, Ill., assignor to Sunbeam Corporation, Chicago, Ill., a corporation of Illinois

Application May 29, 1948, Serial No. 29,972

14 Claims. (Cl. 38—79)

This invention relates to flatirons and more particularly to novel support means for a flatiron that is capable of maintaining the flatiron, when temporarily out of use, in a raised position above an ironing board or work surface.

In certain types of flatirons it is the usual practice to set the iron up on its rear end on the ironing board when the ironing operation is temporarily stopped. This practice is objectionable in several respects in that it causes wear and strain on the cord which is twisted more than 90° from its normal position; it exposes the entire heating surface of the sole plate so that it may be brushed against by the user's arm; and this up-ended position is relatively unstable whereby the iron may fall off the ironing board, thus presenting a further hazard especially to small children. Furthermore, certain types of steam irons cannot be up-ended in the conventional manner without creating an undesirable condition in the water reservoir. It is preferable, therefore, that in the out-of-use position the iron be tipped only slightly and not all the way back over its rear end. However, supporting mechanism conventionally employed for this purpose are relatively complicated and expensive considering the competitive nature of this class of merchandise since they include latching and unlatching mechanisms requiring manual manipulation on the part of the user.

A principal object of the present invention is to provide a relatively simple flatiron support means which avoids the use of complicated and expensive latching mechanisms and which avoids the necessity of the operator performing conscious mental manipulations, such as depressing latch release buttons and the like.

Another object of the invention is to provide support means which utilizes a snap spring system arranged to permit the iron to snap into an inclined elevated position with respect to a support member after a preselected upward tilting of the iron about its rear edge is effected and which permits the support member to snap into a retracted position after a preselected downward movement of the iron from its raised position, about the rear edge is effected.

Other objects and advantages will become apparent from the following description in connection with the drawings, in which—

Figure 1 is a side view of a flatiron embodying one form of the present invention, shown in its supported position;

Fig. 2 is a fragmentary bottom view of the iron showing the support member in a retracted position;

Fig. 3 is a fragmentary top view of the support member alone;

Fig. 4 is a fragmentary longitudinal sectional view of Fig. 2 taken on line 4—4 showing the overcenter snap mechanism and the support in its retracted position;

Fig. 5 is a view similar to Fig. 4 showing the support in its extended or supporting position;

Fig. 6 is a transverse sectional view of the overcenter spring system taken on line 6—6 of Figs. 2 and 4, and

Fig. 7 is a sectional view of Fig. 6 taken on line 7—7.

Referring now more particularly to the drawing, the flatiron comprises a body generally designated 1 and a handle 2 fixedly secured thereto, the latter carrying the heat regulating control wheel 3. These are conventional and form no part of the present invention except as they may be employed in combination therewith.

The body 1 comprises the usual sole plate 4 and cover 6 which in the present instance extends beyond the rear of the sole plate to provide a rearwardly extending hood 7 for a snap acting mechanism utilized for a purpose to be hereinafter described.

The body 1 is pivotally mounted at its rear end on a support for maintaining the iron in an inclined elevated position as shown in Figure 1 and generally designated by the numeral 8. In the present instance the support 8 is formed by a U-shaped member (see Fig. 3) having a bridging portion 8a disposed beneath the hood 7 at the rear of the iron and a pair of forwardly extending legs 9 shaped to be received in edge recesses 11 formed along opposite sides of the bottom of the sole plate. When the support 8 is in a retracted position as shown in Fig. 2 its bottom surface 12 is substantially flush or slightly recessed with respect to the bottom surface 13 of the sole plate 4 so that the iron may pass readily over a work piece 14 such as a cloth on an ironing board or the like. One edge of the bridging portion 8a is folded back on itself to form an upper portion 16 (see Fig. 4) extending toward the front end of the iron and having a pair of spaced downwardly facing grooves 17 formed on its underside. Between the grooves 17 is an adjusting screw 18 threaded through the upper portion 16 and having a pivot point 19 projecting above the upper portion 16. A hole 21 in the lower portion of the bridging portion 8a provides access to the screw 18 for adjustment purposes.

A bracket 22 having a generally L-shaped cross section is mounted at the rear of the iron and on top of the sole plate 4 as by spot welding so that

it has a portion 23 extending upwardly from the sole plate. A bracket 24 having a generally C-shaped cross section as shown in Fig. 4 is secured to the upstanding portion 23 as by screws 26. The bracket 24 extends transversely of the iron. The top arcuate shaped portion 27 of the bracket 24 terminates in a knife edge 28 at each end of the bracket. The bottom arcuate shaped portion is slotted intermediate its ends (see Fig. 6) to define spaced portions 29 each terminating in an upwardly facing knife edge 31 pivotally disposed respectively in the grooves 17 on the upper portion 16 of the bridging member 8a. Interposed between the top portion of the bracket 24 and the adjusting screw 18 is a resilient compression member 32. In the present instance the compression member comprises a flat sheet of spring material folded back on itself and having a generally rectangular shaped top leaf 33 and a generally triangular shaped bottom leaf 34. The top leaf is formed with grooves 36 shaped to pivotally receive knife edges 28 as shown in Fig. 6 and the lower leaf has a depression 37 pivotally receiving an adjusting screw point 19. This construction provides a three point support for the spring member 32 and insures that the spring member 32 is in a stably assembled position.

It is to be understood that the resilient member 32, the bracket 24 and the adjusting screw 18 define an overcenter snap spring system. The spring system has an axis of maximum stress with alternate positions of reduced stress. The axis of maximum stress in this instance is defined by alinement of the knife edges 28 and 31 and pivot point 19 and indicated by the broken line A—A in Figs. 4 and 5.

The operation of the support means is as follows: Assume that the iron is heated and in use. When it is desired to temporarily discontinue ironing it is only necessary to grasp the handle 2 and tip the front portion of the iron upwardly while keeping the rear portion of the iron in engagement with the work surface. The front end of the iron need only be raised upwardly with respect to the support 8 until the pivot edges 28 of the bracket 24 are moved slightly to the right of the line A—A as viewed in Fig. 4. The snap spring system then being in an unstable position moves the iron with a snap action to its final inclined position shown in Figs. 1 and 5. The iron will be stably maintained in its inclined position as long as desired. When it is desired to continue ironing the handle is grasped and the front end of the iron is pushed downwardly until the pivot edges 28 move slightly to the left of the axis A—A as viewed in Fig. 4. Thereafter the spring system being in an unstable position moves the support 8 upward with a snap movement to its retracted position in which the legs 9 are received in the grooves 11 formed on the bottom of the sole plate.

The screw 18 serves the dual purpose of providing a convenient means for assembling and disassembling the spring system as well as adjusting the compression of spring 32 to any desired value.

The present invention provides a supporting mechanism for flatirons wherein the user has only to tilt the iron slightly backward against the working surface whereby the iron automatically positions itself to an inclined position in which the sole plate is moved out of contact with a working surface. Moreover when it is desired to re-use the iron all the operator has to do is push the handle forward as is done in a normal ironing operation. It is to be understood that

by the use of an overcenter snap spring mechanism in the manner described an extremely simple supporting device is provided that makes possible a construction which avoids the use of complicated manual latching mechanisms heretofore conventionally employed.

While a particular form of the present invention has been shown, it is apparent that minor changes may readily suggest themselves to others skilled in the art without departing from the spirit and scope of the invention.

I claim:

1. In combination, a flatiron having a body with a smooth bottom surface movable between a first position in which said surface is inclined with respect to a work surface and a second position in which said bottom surface rests on said work surface, a support, means for pivotally mounting said support to the rear of said body, said support having a leg extending forwardly of the iron, said leg shaped to engage the work surface when the body is inclined in said first position and being disposed above said bottom surface when the latter engages said work surface and an overcenter snap spring system disposed between said support and said body and having an axis of maximum stress and positions of reduced stress disposed on either side of said axis of maximum stress, said spring system comprising spring means connected to said body and said support and operable to maintain said support in a position to hold said body inclined with respect to the work surface in one position of reduced stress and operable to maintain said support above the bottom surface of the body in the other position of reduced stress, said spring means causing said support to move with a snap action when said spring system passes in either direction through its axis of maximum stress, whereby when said iron is moved from an inclined position toward the work surface said leg moves into its retracted position with a snap action.

2. In combination, a support formed by a generally U-shaped member having a bridging portion and spaced leg portions, a body having spaced recesses formed on its bottom surface for receiving said legs and being pivotally connected at one end to said bridging portion, said legs when disposed in said recesses being substantially flush with the bottom surface of the body, said body being movable upwardly about the pivotal connection to a position in which the body is inclined with respect to the support and downwardly from its latter position to a position in which the legs are retracted in their respective recesses, and an overcenter spring system disposed between said bridging portion and said body including an overcenter spring stressed between said bridging portion and said body, said spring system having capacity to maintain the body and the legs in their respective positions and operable to move said legs to a position corresponding to the inclined position of said iron with a snap action when the body is moved upwardly upon moving the spring system overcenter in one direction and operable to move the legs to their retracted position with a snap action when the body is moved downwardly to move the spring system overcenter in the other direction.

3. In combination, a body arranged to be swung upwardly about one end thereof to a position in which it is inclined to a work surface and to be swung downwardly about the end from its inclined position to a position in which the body rests on the work surface, a support pivotally

mounted at said one end of the body and arranged to engage the work surface when the body is inclined thereto to maintain the body in its inclined position and retractable to a position in which the support is disposed above the surface of the body engaging the work surface and an overcenter snap spring system having an axis of maximum stress and positions of reduced stress on opposite sides of said position of maximum stress, said spring system being operable to hold said support in a position to maintain the body in an inclined position with respect to the work surface while in one position of reduced stress and to maintain the support above the work surface when the body rests on the work surface and while said spring system is in the other position of reduced stress, said spring system arranged when the body is moved upward through the axis of maximum stress to move said support to its position corresponding to the inclined position of said body with a snap action and when the body is moved downwardly through the axis of maximum stress to move the support to its retracted position with a snap action.

4. The arrangement set forth in claim 3 including means for adjusting the stresses in said spring system.

5. In combination, a support shaped to rest on a work surface, a flatiron overlying said support and being formed with a recess to receive said support so that the latter may be disposed in a substantially flush relation with the bottom of the flatiron, said flatiron being movable upwardly about one of its ends to a position in which the bottom of the iron is inclined to said support and movable downwardly from its upper position to a position in which the support is retracted in said recess, a bracket rigidly mounted on said body and movable in unison therewith between preselected positions, said bracket having spaced opposed knife edges, one of said edges being pivotally connected with said support, a projection mounted on said support and extending to a position intermediate the spaced knife edges, a compression member disposed between said other knife edge and said projection, said bracket, compression member and projection forming a snap spring system having an axis of maximum stress whereby movement of the bracket to move the knife edge through the axis of maximum stress in one direction causes said flatiron and support to be moved outwardly relative to each other with a snap action and movement of the bracket in the opposite direction to move the same knife edge through the axis of maximum stress causes said support and flatiron to be moved toward each other with a snap action.

6. In combination, a support shaped to rest on a work surface, a flatiron overlying said support and being formed with a recess to receive said support so that the latter may be disposed in a substantially flush relation with the bottom surface of the flatiron, said flatiron being movable upwardly about one of its ends to a position in which the bottom of the iron is inclined to said support and movable downwardly from its upper position to a position in which the support is retracted in said recess, a bracket mounted on said flatiron, means for pivotally mounting said support on said bracket, a projection mounted on said support adjacent said pivotal mounting, a stressed spring member having a connection with both said projection and said bracket and forming therewith a snap spring system having an axis of maximum stress and positions of re-

duced stress on either side of said axis, said spring system being arranged so that movement thereof in one direction through the axis of maximum stress causes relative movement of said flatiron and support in a direction away from each other with a snap action and movement thereof in the opposite direction through the axis of maximum stress causes relative movement of said flatiron and support in a direction toward each other with a snap action.

7. The combination recited in claim 6 in which said projection is in the form of an adjustable abutment for varying the stresses in the spring system.

8. A flatiron comprising an ironing body, a support attached to said body for movement from a retracted position to an extended position in order to support said body in an elevated position with reference to the ironing work surface, power means connected to said support for biasing it to said extended position, said power means normally being ineffective to bias said support to said extended position when the iron is in its ironing position on the work surface and the support is in said retracted position, and an element controlling said power means to render it effective to bias said support to said extended position operating responsively to the engagement of said element with said work surface as said iron body is tilted upwardly with reference to said work surface about a predetermined axis.

9. A flatiron comprising an ironing body, a support pivoted to said body for angular movement on a predetermined axis from a retracted position to an extended position in order to support said body in an elevated position with reference to the ironing work surface, a spring connected to said support for operating it to said extended position, said spring connected thereto so that when said support is in said retracted position said spring is positioned so that its force is nullified to operate said support to said extended position, and means movable to shift said spring angularly to a position wherein its force becomes effective to bias said support to said extended position, said last-named means being moved to cause said angular shift of said spring by the engagement of said means with said work surface when said body is manually tilted upwardly about said predetermined axis.

10. A flatiron comprising a body, a support connected to said body for motion with reference thereto from a retracted position to an extended position in order to support said body in an elevated position with reference to the ironing work surface, power operating means interconnecting said body and support biasing said support to said retracted position or to said extended position depending upon the relative position of said support with reference to said body on one side or the other of a critical position, and means connected with said support engageable with said work surface when said body is inclined upwardly from said work surface to hold said support and prevent upward movement thereof along with said body as said body continues to incline upwardly and thereby cause said support and body to move with relation to each other from said one side of said critical position to said other side thereof, whereupon said power means becomes effective to bias said support to said extended position.

11. A flatiron comprising a body, a support for said body for holding it in a raised position above the work surface, said support being pivoted to

said body on a transverse axis at the rear and extending forwardly therefrom, and said support also being movable from a retracted position with reference to said body to an extended body-supporting position wherein said body is held in a raised position above the ironing work surface, an over-center spring connected to said body and support operating when the spring is on one side of a critical position to hold the support in said retracted position for normal ironing operations and operating to hold said support in said extended position and hold said body in said raised position when the spring is on the other side of said critical position, and a trigger extending rearwardly from said support for engagement with said work surface when the forward end of said body is tilted upwardly manually through a predetermined degree of movement and for throwing said spring over center from said one side to said other side of said critical position, whereupon said spring is rendered effective to support said body in said raised position above said work surface.

12. Mechanism for holding a flatiron in a non-ironing position comprising, in combination with the iron proper, a support pivotally attached to the iron and including a first portion engageable with the surface on which the iron is supported to support the iron above said surface and a second portion, and overcenter-spring means acting between the iron proper and said support and operative to move said support to a position to support said iron in said non-ironing position upon a preselected tilting movement of the iron about its rear edge to cause said second portion to engage said surface and initiate overcenter movement of said spring means, the iron being movable to said ironing position by downward manual pressure on the iron, said spring means automatically retaining said support in a position so as not to interfere with said iron in said ironing position and moving to said last-mentioned position in response to said downward movement of the iron.

13. A flatiron lift for a flatiron having support means which includes a support member pivotally mounted on the flatiron and movable between a

retracted position and an iron supporting position, said support including a first portion engageable with the surface on which the iron is supported to support the iron above said surface and a second portion, an overcenter snap spring system acting between the support member and the flatiron and arranged to effect snap movement of the support member to said iron supporting position in response to a slight upward tilting of the iron about its rear edge to cause said second portion to engage said surface and initiate overcenter movement of said snap spring system, and to effect snap movement of the support member to its retracted position after a predetermined downward movement of the iron from its raised position.

14. A flatiron lift comprising support means for supporting the flatiron in an inclined elevated position, said support means including a first portion engageable with the surface on which the iron is supported to support the iron above said surface and a second portion, an overcenter snap spring system arranged to be actuated in response to a slight upward tilting of the iron about its rear edge to cause said second portion to engage said surface and initiate overcenter movement of said snap spring system thereby to cause said support to move said iron from its normal ironing position to the inclined position, said overcenter snap spring system being actuated in response to a slight downward movement of the iron when the latter is in its inclined position, said spring system including a member arranged to move to a locking position at one side of a center line to maintain said iron in said inclined elevated position and to a retracted position at the opposite side of said center line to permit normal use of the iron.
